PHILIP A. MYERS, OF ASHLAND, OHIO, ASSIGNOR TO F. E. MYERS AND BROTHER, OF ASHLAND, OHIO, A COPARTNERSHIP CONSISTING OF FRANCIS E. MYERS AND PHILIP A. MYERS.

PUMP.

1,191,453.

Specification of Letters Patent. Patented July 18, 1916.

Application filed September 18, 1915 Serial No. 51,298.

To all whom it may concern:

Be it known that I, PHILIP A. MYERS, a citizen of the United States, residing at Ashland, in the county of Ashland and State of Ohio, have invented certain new and useful Improvements in Pumps, of which the following is a specification, reference being had therein to the accompanying drawing.

This invention relates to a pressure controlling device which is applicable to various mechanisms but is more particularly designed for use with spray pumps, or the like, in which it is desired to interrupt the operation of the pumping instrumentalities when the resistance to the movement of the piston has become abnormal, without interrupting the application of power to the operating devices. Pumps of this kind have been heretofore designed but for the most part they have not been of a satisfactory construction or operation.

The object of the present invention is to provide a pump of this type in which the controlling mechanism will be of a very simple and of a highly practical character, thus not only cheapening the construction of the pump but also rendering it more certain in its operation and less liable to get out of order or to fail to operate.

To this end, it is a further object of the invention to provide improved means for applying the controlling spring to the operating mechanism, and to so arrange the mechanism that a short spring supported solely by the connecting rod may be utilized to yieldably control the action of the connecting rod.

In the accompanying drawings, Figure 1 is a side elevation, partly in section, of a power-operated spray pump embodying my invention and showing the pump operating devices in their normal operative positions; Fig. 2 is a similar view showing the positions of the parts when the pressure has become normal; and Fig. 3 is a detail view, partly in section, of the two part connecting rod and its controlling spring.

In these drawings I have shown the invention as applied to a power spray pump of a known character. This pump comprises a base 1 upon which is mounted a cylinder, or cylinders, 2. In the present instance the pump is a double acting pump and two cylinders are provided. Mounted in each cylinder is a piston 3 which serves

to draw the fluid in through an inlet pipe 4 and to force the same out through an air chamber 5 and discharge pipe 6. This discharge pipe is usually connected with a tank in which the fluid is stored under air pressure and to which are connected the hose and nozzle, or other distributing devices. This tank is constructed to withstand a certain predetermined pressure and to avoid injury to the tank and possible injury to the operator it is essential that the pressure should not rise materially above the predetermined amount. Relief valves are commonly used to control this pressure but their operation is unsatisfactory, principally because of the corrosion due to the character of the spraying fluids.

The operating mechanism for the pump may be of various kinds, but preferably comprises a crank shaft 7 journaled in uprights 8 carried by the base 1, and driven by means of gearing 9 and 10 from a shaft 11 to which power may be applied either by a belt or in any other suitable manner. To control the movement of the movable part of the mechanism I have interposed between the same and another part of the apparatus a two part connecting rod or toggle, the two parts of which are held normally against relative movement by a spring. In the present embodiment of the invention the toggle serves to transmit power from the shaft to the piston and to this end a toggle is interposed between the crank shaft and each piston. The two members of each toggle or connecting rod, as shown at 12 and 13, are pivotally connected one to the other, at 14, and, at those ends remote from the axis of said connection, are pivotally connected respectively to the crank shaft and to the piston 3, as shown at 1 and 16. The movements of the two members of the connecting rod about their intermediate axis 14, by which they are connected one to the other, are so controlled that this axis cannot move into alignment with the axis, 15 and 16, of the connections between the ends of the rod and the piston and crank shaft, respectively. The movement of this intermediate axis toward a line extending through the axes 15 and 16 of the rod is limited by coöperating parts of the two members of the rod. As here shown, one member, 12, has a projection or lug 17 extending beyond the axis 14 and arranged to engage a part or lug 18 car-

ried by the other member, 13, of the rod when the two parts of the rod are moved toward alinement, the arrangement of the parts 17 and 18 being such that the axis 14 5 cannot be moved into line with the axes 15 and 16. Preferably, one of the parts, as here shown the part 18, is provided with a cushion, such as a block of leather, to deaden the sound and to absorb the shock due to the 10 contact of these parts.

A spring 19 is connected with the two members of the rod in such a manner as to resist their movement in a direction to carry the intermediate axis 14 away from the line 15 extending through the axes 15 and 16, the strength of this spring being such that it will prevent any movement of either member of the rod about the axis 14 so long as the resistance to the movement of the piston does 20 not become abnormal, that is, as the pressure in the tank does not exceed a certain predetermined limit. So long as the resistance to the piston is normal the spring renders the connection between the two 25 members of the connecting rod a rigid one and the connecting rod operates in the same manner as an ordinary rigid connecting rod. When the pressure exceeds said predetermined limit and the resistance to the movement 30 of the piston becomes abnormal, the two members of the connecting rod will be moved about their connecting axis, 14, and this axis will be moved farther out of alinement with the axes 15 and 16, this movement 35 being against the tension of the spring. This relative movement of the two members of the connecting rod gradually increases until the piston 3 is held against all movement and the movement of the crank shaft 40 is absorbed by the relative movement of the two members of the connecting rod. As soon as the resistance to the movement of the piston becomes again normal, or approaches normal, the spring will move the 45 two members in opposite directions and the axis, 14, will be moved toward its normal position, thus gradually restoring the normal operation of the pump. The spring 19 may be connected with the two members of 50 the connecting rod in different manners. I prefer the construction shown herein, because of its simple character, compact arrangement and great strength. In this arrangement I have used the compression 55 spring 19 and have connected one end of this spring to the member 12 of the connecting rod and have connected the other end of the spring to a bifurcated extension or finger 20 rigidly secured to and forming a part 60 of the member 13 of the connecting rod and extending beyond the axis 14, the arrangement being such that the points of connection of the spring with the two members of the connecting rod are adjacent one to 65 the other and approximately in alinement

with the spring. In the present instance the connections are made by pivotally connecting a rod 21 to the arm 12 at a point a short distance removed from the axis 14 and mounting on this rod two flanged plates 22 and 23 70 which form seats to receive the ends of the spring 19. The plate 23 is held on the pivoted rod by means of adjustable nuts 24 and 25, by means of which its position can be varied and the tension of the spring regulated. The plate 22 is loosely mounted on the pivoted rod and has projections or lugs 26 seated in sockets or recesses 27 formed in the two parts of the finger 20 of the member 13 of the connecting rod, the arrangement of the seats being such as to form alined bearing for the lugs and to permit relative movement of the parts about the axis of said bearings. It will be apparent that the expansion of the spring 19 will tend to move 85 the points of connection between the two ends of the spring and the two members of the connecting rod toward each other and thus move the two members of the connecting rod toward their extended positions, that 90 is, their positions nearest alinement, and likewise that the movement of the two members in the other direction about their axis, 14, which tends to move said axis out of its normal position, will separate the points of connection of the spring and thus compress 95 the spring.

The operation of the device will be readily understood from the foregoing description and it will be apparent that I have provided a controlling mechanism which is very simple in its construction, which is certain in its operation and which is of a very strong, durable character. Further, it will be apparent that the device is readily adjustable to cause the same to yield at different pressures; and further, that the device comprises very few parts; and that the character and arrangement of these parts is such that they will not readily get out of 100 order or lock or bind in such a manner as to interfere with or prevent the operation of the mechanism in the prescribed manner.

While the invention was primarily designed for, and has been illustrated as applied to, a spray pump it will be apparent that it can be applied to pumps of other kinds or to mechanism other than pumps where the operation is similar and the device would be useful, and further, it will be understood that the construction shown and described has been chosen for the purpose of illustration only and that I do not wish to be limited thereto, as obvious modification will occur to a person skilled in the art. 115

Having thus fully described my invention, what I claim as new and desire to secure by Letters Patent, is:—

1. In a pump, the combination, with a piston, and a crank shaft, of a two part 120

connecting rod interposed between said piston and said shaft, the two part rod having its ends pivotally connected, respectively, with said shaft and said piston and having its two members pivotally connected one with the other on an axis arranged between but out of alinement with the axes of the first-mentioned connections, and a spring carried by said rod and acting thereon to hold the two members thereof against relative movement during the normal operation of said pump and to permit said members to have relative movement when abnormal resistance is offered to the movement of said piston.

2. In a pump, the combination, with a piston, and a crank shaft, of a two part connecting rod interposed between said piston and said shaft, the two part rod having its ends pivotally connected, respectively, with said shaft and said piston and having its two members pivotally connected one with the other on an axis arranged between but out of alinement with the axes of the first-mentioned connections, the two members of said rod having parts co-operating to prevent said intermediate axis from being moved into alinement with the axes of the said first-mentioned connections, and a spring carried by said rod and acting thereon to hold the two members thereof normally against relative movement about said axis.

3. In a pump, the combination, with a piston, and a crank shaft, of a two part connecting rod interposed between said piston and said shaft, the two part rod having its ends pivotally connected, respectively, with said shaft and said piston and having its two members pivotally connected one with the other on an axis arranged between but out of alinement with the axes of the first-mentioned connections, and a spring connecting both members of said connecting rod and acting thereon to hold said members against relative movement during the normal operation of said pump and to permit said members to have relative movement when abnormal resistance is offered to the movement of said piston.

4. In a pump, the combination, with a piston, and a crank shaft, of a two part connecting rod interposed between said piston and said shaft, the two part rod having its ends pivotally connected, respectively, with said shaft and said piston and having its two members pivotally connected one with the other on an axis arranged between but out of alinement with the axes of the first-mentioned connections, one member of said rod having a part extending beyond such intermediate axis and arranged to engage a part carried by the other member of said rod to limit the movement of said intermediate axis toward a line extend-

ing through the two first-mentioned axes, and a spring connected with the two members of said rod and tending to move said intermediate axis toward said line.

5. In a pump, the combination, with a piston, and a crank shaft, of a two part connecting rod interposed between said piston and said shaft, the two part rod having its ends pivotally connected, respectively, with said shaft and said piston and having its two members pivotally connected one with the other on an axis arranged between but out of alinement with the axes of the first-mentioned connections, the two members of said rod having parts adapted for connection with the respective ends of a spring and arranged to be moved toward or away from each other when said members are moved about said intermediate axis, and a spring connected with said parts of said members.

6. In a device of the character described, the combination, with a driving member and a driven member, of a two part connecting rod having its two parts pivotally connected one to the other and its ends pivotally connected, respectively, with said driving member and said driven member, means to hold the axis on which the two parts of said rod are connected one to the other out of alinement with the axes of the ends of said rod, and a spring connected to and acting directly upon the two parts of said rod and tending to resist the movement of the two parts of said rod about the axis on which they are connected one to the other.

7. In a device of the character described, the combination, with a driving member and a driven member, of a two part connecting rod having its two parts pivotally connected one to the other and its ends pivotally connected, respectively, with said driving member and said driven member, means to hold the axis on which the two parts of said rod are connected one to the other out of alinement with the axes of the ends of said rod, one of said rods having a part extending beyond the axis on which the two parts of said rod are connected, and a spring connected with the two parts of said rod on the same side of said axis.

8. In a device of the character described, the combination, with a driving member and a driven member, of a two part connecting rod having its two parts pivotally connected one to the other and its ends pivotally connected, respectively, with said driving member and said driven member, means to hold the axis on which the two parts of said rod are connected one to the other out of alinement with the axes of the ends of said rod, one part of said rod having a projection extending beyond the axis on which said rods are connected, a rod pivotally mounted on one part of said con-

- necting rod, two plates mounted on said pivoted rod, a spring coiled about said pivoted rod between said plates, means carried by said pivoted rod to limit the movement of 5 one of said plates, and a connection between the other of said plates and the projection from said part of said connecting rod to control the movement of the other plate relatively to said pivoted rod.
- 10 9. In a device of the character described, the combination, with a driving member and a driven member, of a two part connecting rod having its two parts pivotally connected one to the other and its ends pivotally connected, respectively, with said driving member and said driven member, means to hold the axis on which the two parts of said rod are connected one to the other out of alinement with the axes of the ends of said rod,
- 15 20 one part of said rod having a finger extending beyond said axis, and a spring having one end connected with said finger and having its other end connected with the other part of said connecting rod adjacent to said finger.
10. In a device of the character described, the combination, with a driving member and a driven member, of a two part connecting rod having its two parts pivotally connected one to the other and its ends pivotally connected, respectively, with said driving member and said driven member, means to hold the axis on which the two parts of said rod are connected one to the other out of alinement with the axes of the ends of said rod, one part of said connecting rod having a finger extending beyond said axis and having a seat, a supporting rod pivotally connected to the other part of said connecting rod adjacent to the seat in said finger, a spring coiled about said pivoted rod, a plate mounted on said rod and held against movement in one direction to form a seat for one end of said spring, a second 45 plate loosely mounted on said pivoted rod to form a seat for the other end of said spring and having a lug extending into the seat in said finger.
11. In a pump, the combination, with a 50 piston, and a crank shaft, of a two part connecting rod interposed between said piston and said crank shaft and means carried by said rod for holding the two parts of said connecting rod normally in their extended 55 positions and for permitting relative movement of the two parts of said rod when abnormal resistance is offered to the movement of said piston.
12. In a mechanism of the character de- 60 scribed, a movable member, a controlling device for said movable member comprising a toggle having one end pivotally connected with said movable member and having its other end pivotally connected with another 65 part of said mechanism, the arms of said

toggle having parts coöperating to prevent the intermediate axis of said toggle from being moved into alinement with the axes at the ends of said toggle, and a spring carried by said toggle and acting thereon to hold said parts of said arms normally in engagement.

13. In a mechanism of the character described, a movable member, a controlling device for said movable member comprising 75 a toggle having one end pivotally connected with said movable member and having its other end pivotally connected with another part of said mechanism, one arm of said toggle having a stop near the intermediate 80 axis of said toggle and the other arm of said toggle having a part projecting beyond said intermediate axis and arranged to engage said stop and prevent said intermediate axis from being moved into alinement 85 with the axes at the ends of the arms of said toggle, and a spring carried by said toggle and acting to hold said projection and said stop normally in engagement.

14. In a mechanism of the character described, a movable member, a controlling device for said movable member comprising 90 a toggle having one end pivotally connected with said movable member and having its other end pivotally connected with another 95 part of said mechanism, one arm of said toggle having a stop near the intermediate axis of said toggle and the other arm of said toggle having a part projecting beyond said axis to engage said stop and prevent said 100 intermediate axis from being moved into alinement with the axes at the ends of the arms of said toggle, a cushion interposed between said stop and said part of said last-mentioned arm, and a spring carried by said 105 toggle and acting to hold said projection and said stop normally in engagement.

15. In a mechanism of the character described, a movable member, a controlling device for said movable member comprising 110 a toggle having one end pivotally connected with said movable member and having its other end pivotally connected with another part of said mechanism, one arm of said toggle having a stop near the intermediate 115 axis of said toggle and having a part ex- tending beyond said axis, the other arm of said toggle having a projection extending beyond said intermediate axis and arranged to engage said stop and prevent said intermediate axis from being moved into alinement with the axes at the ends of said 120 toggle, a spring connected at one end with that part of the first-mentioned arm which projects beyond said intermediate axis and connected at its other end with the last-men- tioned arm at a point adjacent to said part of the first-mentioned arm.

16. In a pump, the combination, with a 130 piston, and a crank shaft, of a two part

connecting rod interposed between said piston and said shaft, the two part rod having its ends pivotally connected, respectively, with said shaft and said piston and having its two members pivotally connected one with the other, and a spring adapted to travel with said rod and to act thereon to hold the two members thereof against relative movement during the normal operation 10 of said pump and to permit said members

to have relative movement when abnormal resistance is offered to the movement of said piston.

In testimony whereof, I affix my signature in presence of two witnesses.

PHILIP A. MYERS.
